US00D973858S

(12) **United States Design Patent** (10) **Patent No.:** **US D973,858 S**
(45) **Date of Patent:** **** Dec. 27, 2022**

(54) **AIR PURIFIER**

(71) Applicant: **Blueair AB**, Stockholm (SE)

(72) Inventors: **Erik Oskar Juhlin**, Stockholm (SE);
Jan Markus Mikael Puranen,
Stockholm (SE)

(73) Assignee: **Blueair AB**, Stockholm (SE)

(**) Term: **15 Years**

(21) Appl. No.: **29/759,546**

(22) Filed: **Nov. 24, 2020**

(30) **Foreign Application Priority Data**

May 27, 2020 (EM) 007972278-0001
May 27, 2020 (EM) 007972278-0003

(57) **CLAIM**

The ornamental design for an air purifier, as shown and
described.

DESCRIPTION

FIG. 1 is a perspective view of a first embodiment of our
new design for an air purifier;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the figures depict portions of the
air purifier that form no part of the claimed design.

1 Claim, 6 Drawing Sheets
